Inventor:

John D. Burwell,
by P. D. Herbold, Attorney

UNITED STATES PATENT OFFICE.

JOHN J. BURWELL, OF CENTRAL COVINGTON, KENTUCKY.

FUEL-DEFLECTOR FOR MECHANICAL STOKERS.

SPECIFICATION forming part of Letters Patent No. 789,486, dated May 9, 1905.

Application filed June 17, 1904. Serial No. 213,048.

To all whom it may concern:

Be it known that I, JOHN J. BURWELL, a citizen of the United States, residing at Central Covington, in the county of Kenton and State 5 of Kentucky, have invented certain new and useful Improvements in Fuel-Deflectors for Mechanical Stokers, of which the following is a specification.

My invention relates to fuel-deflectors for 10 mechanical stokers, and has for its object the providing of a deflector capable of directing the fuel to the various parts of the fire-box. It is especially applicable to locomotives or may be used in other furnaces. It is an improvement applicable to the device shown and 15 described in my Patent No. 759,859, granted me May 17, 1904, for improvement in mechanical stokers.

The invention will be readily understood 20 from the following description and claims and from the drawings, in which—

Figure 1 is a perspective view of my improved device applied, partly broken away for better illustration of parts. Fig. 2 is a 25 central longitudinal section of the same on the line $x-x$ of Fig. 4, showing the deflector in edge elevation in one position in full lines and in another assumed position in dotted lines. Figs. 3 and 4 are rear views of my improved 30 device, partly broken away, each showing the deflector in one position in full lines and in another assumed position in dotted lines.

The figures indicate a number of the various positions into which the deflector may be 35 thrown.

A represents the fire-box of a locomotive or may represent any suitable furnace, to which a door B is hinged. The door has an opening C, about which there is a thimble D 40 on the door. The inner end of the thimble is indented, as shown at d , for accommodating the stem of the deflector. A fuel-chute E is secured to the thimble, as by a pin e taking through apertures in the chute and thimble, the thimble forming a continuation of the 45 chute. The chute may at its other end connect with any suitable hopper, fuel-conveyer, or stoker. It may have connection similar to the fuel-chute shown and described in my 50 aforesaid patent.

F is a deflector and preferably comprises a deflector-plate f and a stem f' . The stem passes through an opening b in the door. The deflecting-plate preferably has a concave side f^2 and a convex side f^3 and is arranged to 55 have either of its sides presented to the mouth of the chute, thus making it reversible. When the concave side is presented to the mouth of the chute, it forms a channel along which the fuel may be directed for being conveyed or 60 projected to remoter parts of the furnace or fire-box, dependent on the angle at which the plate is presented to the mouth of the chute, as hereinafter explained. When the convex side of the deflector-plate is presented to the 65 mouth of the chute, a bulged face is presented to said mouth and the coal is spread over a greater area in the fire-box, the part of the fire-box to which the fuel is conveyed being 70 also in this case dependent on the angle at 70° which the plate is presented to the mouth of the chute. A turning movement is permitted 75 the deflector-plate. Means are also provided for bringing the deflector-plate closer to or farther from the mouth of the chute and for changing the angle of the deflector-plate with relation to said mouth. In this manner the fuel may be directed to any part of the fire-box or dropped at the front part thereof, as 80 may be desired.

G is a hanger. It comprises links g , pivoted on lugs g' to the thimble, and a bearing g^2 , to which the links are articulated, as at g^3 . The bearing has a rib g^4 , taking into grooves 85 on the stem f' .

A curved guide H is pivoted at h to the door B for permitting the guide to swing up and down. A spanner-piece I slides on the guide and has an aperture i , through which the stem f' passes. A set-screw i' takes 90 against the stem through the spanner-piece and firmly secures the stem between the set-screw and guide for fastening the parts securely in adjusted position. The stem has annular grooves f^5 , into which the end of the 95 set-screw and rib g^4 may take for positioning the stem at various points of its length on the guide. The stem has a handle f^6 , by which the deflector-plate f may be manipulated. The stem may be moved longitudinally for mov- 100

ing the deflector-plate toward or away from the mouth of the chute or feeder E or turned upon its longitudinal axis for changing the angle of the deflector-plate about its longitudinal axis and for reversing the said plate or turning it upside down for presenting either its concave or convex side to the mouth of the chute. The stem may also be swung on the pivots of the hanger for throwing the deflector-plate more or less upwardly in front of the mouth of the chute, and the curved guide may also be swung up or down on its pivots for aiding in this movement. The inner end of the deflector-plate may be thrown inwardly and upwardly sufficiently for receiving the fuel upon the deflector-plate and directing it downwardly at the front end of the fire-box, and the indentation d in the end of the chute accommodates the deflector-stem for extreme position of this kind. The deflector-plate deflects the fuel, which is usually in crushed state when fed through the chute, to any desired part of the fire-box.

Having thus fully described my invention, what I claim as new, and desire to secure by Letters Patent, is—

1. In a mechanical stoker, the combination, with a fuel-chute, of a fuel-deflector comprising an integral deflector-plate and stem movable longitudinally and to various angles with relation to said chute, and reversible for presenting either side of said deflector-plate to the mouth of said chute.

2. In a fuel-deflecting device for mechanical stokers, the combination, with a fuel-chute, of a fuel-deflector, and means permitting turning of said deflector about its longitudinal axis for presenting either side of said deflector to the mouth of said chute and positioning the deflector at various angles to the front of the mouth of the chute, substantially as described.

3. In a mechanical stoker, the combination, with a fuel-chute, of a fuel-deflector having a deflector-plate with a plurality of receiving-

surfaces of different shapes for the fuel, said deflector-plate being movable in the direction of the plane of extension of said deflector-plate, to various angles with relation to the mouth of said chute, and for presenting any 50 of said receiving-surfaces to the mouth of said chute.

4. In a fuel-deflecting device for mechanical stokers, the combination with a fuel-chute, of a fuel-deflecting plate having a channeled side and a bulged side, and means for presenting either of said sides to the mouth of the chute.

5. In a fuel-deflecting device for mechanical stokers, the combination with a fuel-chute, of a fuel-deflecting plate having a channeled side and a bulged side, means for presenting either of said sides to the mouth of said chute, and means for positioning said plate at various angles with relation to said 65 mouth, substantially as described.

6. In a fuel-deflecting device for mechanical stokers, the combination, with a furnace and fuel-chute therefor, of a fuel-deflecting plate having a channeled side and a bulged 70 side inside said furnace, said fuel-deflecting plate having a stem connecting therewith from outside said furnace, means for supporting said stem, said supporting means having pivotal connection with said stem, a curved guide, 75 said stem being adapted to have longitudinal movement with relation to said guide and means for positioning said stem longitudinally of said guide, substantially as described.

7. The combination, in a mechanical stoker, 80 with a fuel-chute, of a fuel-deflector reversible for presenting either of its sides to said chute.

In witness whereof I have signed my name hereto in the presence of two subscribing witnesses.

JOHN J. BURWELL.
